UNITED STATES PATENT OFFICE.

JOSEF KAMIENIECKI, OF CHICAGO, ILLINOIS.

SUBMARINE ARMOR.

1,370,590.

Specification of Letters Patent.

Patented Mar. 8, 1921.

Application filed December 2, 1918. Serial No. 264,986.

To all whom it may concern:

Be it known that I, JOSEF KAMIENIECKI, a citizen of Russia, residing at Chicago, in the county of Cook and State of Illinois, have invented certain new and useful Improvements in Submarine Armor, of which the following is a specification.

This invention relates to submarine or diving armor, and more particularly to a metal sectional armor of this type which by reason of its strength and rigidity is particularly adapted for use in deep sea diving, and an object of the invention is to provide a metal submarine armor which is flexible at its joints or connections under actual working conditions in order to enable the diver, when incased in the armor to have ready use of his arms, hands and legs for performing his necessary duties.

A further object of the invention is to provide a submarine armor as specified, in which the air circulating system embodies a valve casing carried at the rear end of the helmet of the armor, which casing has an inlet chamber and an exhaust chamber with the passage of air therethrough being controlled by flap valves, so as to prevent the passage of exhaled air into the inlet compartment and also to provide a valve mechanism in the said casing whereby the air may be cut off, in case the hose becomes broken, to prevent the flooding of the interior of the armor, and further to provide a relatively small electric fan carried by the armor and having its exhaust arranged for passage into the exhaust or exhaling chamber of the said valve casing, to create an air suction through the armor and maintain fresh and clean air within the helmet of the armor at all times, by drawing the used or exhaled air into the exhaust or exhaling compartment and forcing it outwardly through the outlet or exhaling tube of the ventilating system.

A further object of the invention is to provide means in connection with the submarine armor as specified, which will permit the diver to rise through the water, independently of the usual type of joint employed for this purpose, which means include a propeller and a suitable prime mover therefor, the operation of which is controlled by the operation of a switch at the front of the body portion of the armor, whereby the diver can, at any desired time, operate the switch to permit the operation

of the propeller to force him upwardly through the water.

A still further object of the invention is to provide an armor as specified in which the arm and leg inclosing sections are detachably connected to the body section to permit their quick and easy removal or disconnection from the body to facilitate the placing of the suit upon a diver and also to provide easily operated means for connecting these sections to the body section by fluid tight joints.

Other objects of the invention will appear in the following detailed description, taken in connection with the accompanying drawings, forming a part of this specification, and in which drawings:

Figure 1 is a vertical section through the improved submarine armor.

Fig. 2 is a face view of the armor showing parts in section.

Fig. 3 is a central longitudinal section through one of the arm sections of the armor, and

Fig. 4 is a detail section on the line 4—4 of Fig. 1, illustrating the switch construction for controlling the operation of the propeller and the air circulating fan.

Referring more particularly to the drawings, wherein like characters indicate like and corresponding parts throughout the several views, 1 designates the body or torso incasing portions of the armor which is constructed of relatively thin sheet metal, so as to prevent collapsing thereof, and the consequent upward forcing of the air from the lower portion of the armor into the upper portion or helmet thereof, when the diver first enters the water, and also to prevent the collapsing of the armor against the body of the diver when encountering relatively swift under currents.

The torso engaging portion 1 of the armor is composed of an upper section 2, and a lower section 3 which sections are connected, by threaded portions as indicated at 4, to provide fluid tight joints between the said sections.

The lower section 3 of the torso engaging portion 1 is provided with circular openings in its ends which are adapted to permit the insertion of the hip-engaging members 5 and 6 within this portion of the body of the armor. Each of the hip-engaging portions 5 and 6 is substantially cylindrical in shape, having their uppermost portions cut

away to provide spaces for receiving the hip of the wearer, which cut away portions meet at the inner ends of the said sections as clearly shown in Fig. 2 of the drawings.

- 5 The hip-encompassing portions 5 and 6 are rotatably mounted within the lower section 3 of the body 1 of the armor for independent movement to permit movement of one hip independently of the other and they are 10 confined within the portion 3 of the body 1 by confining or end plates 7 which are attached to the body section 3 by any suitable fastening means such as bolts or the like.

The sections 5 and 6 are each provided 15 with circular openings 8 in their lower portions which have detachably connected thereto, the thigh or upper leg incasing tube 9. These tubes 9 are detachably connected in any suitable manner to the sections 20 5 and 6, and they are provided with annular channels 10 near their lower ends. The annular channels 10 receive the inner ends of set screws 11 which are carried by the coupling members 12, for connecting the 25 tubular sections 9 to the coupling members 12. These coupling members 12 which provide the knee joints comprise outer housing sections 13 in which are rotatably mounted cylindrical members 14. The cylindrical 30 members 14 are mounted for rotation about horizontal axes and they have their upper portions cut away to permit the insertion of the legs of the person wearing the armor therethrough. The cylindrical sections 14 35 are confined within the outer housing sections 13 by detachable end plates 15 and through the medium of the rotary mounting of these members within the housing members 13 and the connection between the housing members 13 to the tubes 9 a universal 40 movement is provided at the knee joint.

The cylindrical rotary members 14 are each provided with openings 16 circular in shape and formed in their lower portions, which 45 openings receive the upper ends of the tubes 17 for inclosing the lower leg section, below the knee, of the wearer of the armor. The tubular sections 17 have their lower ends detachably connected to the upstanding 50 portions 18 of the coupling member 19. These coupling members 19 form a portion of the shoes or foot engaging parts of the armor and they have their lateral end portions open to permit the insertion therein 55 of the cylindrical portion 20 of the foot inclosing sections 21. The cylindrical portions 20 are rotatably mounted within the casing 19 to permit of movement of these sections about horizontal axes to permit the 60 use of the ankle of the wearer. The casing 19 is provided with weighted heel portions 22 to assist the wearer in keeping his feet upon the bottom of the sea or surface upon which he is walking.

- 65 The upper section 2 of the torso incasing

portion of the armor 1 is provided with openings 24 therein at each side and near its upper end to permit the insertion of the arms of the diver therethrough. Flanged collars 25 are mounted in the openings 24, 70 the flanges of which engage against the inner surface of the section 2 about the opening. The collars 25 are externally threaded for threaded engagement with the upper ends of the upper arm inclosing portions 26 75 of the armor and if it is desired, ribs 27 may be formed upon the upper ends of the sections 26 for limiting the inserting movement of their upper threaded ends. The upper sections 26 are laterally threaded as 80 shown at 28 to receive the shoulders of the wearer and their lower ends are provided with annular channels 29 adapted to receive therein set screws 30 for connecting the upper arm inclosing sections 26 to the coupling 85 members 31. The coupling members 31 which are positioned for engagement about the elbow of the diver, have their lateral end portions open to permit the insertion of the cylindrical members 32 therein, which 90 cylindrical members are confined within the casings 31 for rotary movement by detachable end plates 33. The circular or cylindrical members 32 have the forearm inclosing tube 33 connected thereto in any suitable 95 manner as shown at 34 and these tubular sections 35 are provided with annular channels near their outer or lower ends as shown at 36 for receiving the inner ends of the set screws 37 which connect the casing 100 members 38 to the forearm inclosing tube 35 to permit rotary movement of the casing with respect to the tubular sections 35. The casings 38 have their end portions open for permitting the insertion of the cylindrical 105 members 39 therein. The cylindrical members 39 are rotatably confined within the casings 38 by end plates 40 which are detachably connected in any suitable manner to the casings 38. The gloves or hand inclosing portions 41 are connected to the cylindrical members 39 and these cylindrical members being rotatably mounted within the housing or coupling 38, permit wrist 110 movement of the hand or glove portions 41. These hand or glove portions 41 comprise a relatively rigid section 42 having a pocket 43 adapted to receive the fingers of the user and the movable sections 44 adapted to receive the thumbs of the diver. The 115 movable sections 44 are rotatably connected to the sections 42, and have cylindrically formed inner ends 45 adapted to be introduced laterally into correspondingly formed sockets in the sections 42 and held therein 120 by plates 46 suitably secured against the outer side of the section 42.

From the foregoing description, it will be seen that the armor is provided with joints at all of the portions thereof corre- 130

sponding to the joints in the arms and legs, as well as the body of the diver to permit his movement of the arms and legs to properly perform his necessary duties when incased 5 in the armor or suit.

The helmet 50 is provided with the depending threaded flange 51 for detachable connection with the upper end of the section 2 of the torso inclosing body 1. This 10 helmet is provided with an opening 52 in the front face thereof, which is closed by a transparent lens 53 to permit the driver to see his surroundings. The helmet 50 is also provided with an opening 54 in the 15 rear side thereof and a valve casing 55 is attached to the helmet about the opening 54. The valve casing 55 is provided with a central partition 56, dividing the same into an inhaling compartment 57 and an 20 exhaling compartment 58. The openings in these compartments which have communication with the interior of the helmet 50 are covered by perforated plates 59 and flap valves 60 and 61 are provided, being positioned respectively upon the inner and outer 25 sides of the plates 59 in the compartments 57 and 58 for controlling the passage of air through the perforated space 59. For instance the flap valve 60 is positioned 30 against the inner surface of the plates 59 in the compartment 57 so as to allow the inlet of air into the armor but prevent the outlet of air from the armor into the compartment 57 while the flap valve 61 is positioned 35 against the inner surface of the plate 59 of the compartment 58 to permit the inlet of air into the compartment 58 from the armor and prevent the passage of air into the armor, from the compartment. These 40 compartments 57 and 58 have the air supply or inlet hose 62 and the exhaling or outlet hose 63 connected therewith. A rotary valve 45 64 is positioned in the casing 55, for controlling the passage of air from the hoses 63 and 62 into or from the respective compartments with which they communicate. The valve handle 65 is positioned exteriorly 50 of the casing, so that in case either one of the hose 62 or 63 becomes broken, the diver can by rotating the valve, prevent the flooding 55 of the interior of the armor. A hose or conduit 66 has communication with the inlet or inhaling compartment 57 and it has a mouth piece 61 thereon for engagement 60 with the face of the diver, so that the inrush air may be delivered directly to his mouth or nose, as desired, without its passing through the armor, while the exhaled air from the diver is exhausted into 65 the armor and forced therefrom by the action of a rotary fan 68. The fan 68 is positioned within a casing 69 which is pivotally connected as shown at 70 to the torso inclosing body 1 of the armor. An electric 70 motor 70 is positioned within the casing 69

for operating the fan 68 and the exhaust from the fan casing 71 communicates with a conduit or hose 72, the outlet of which is positioned adjacent the inner open end of the compartment 58 to permit the exhausting 75 of the air circulated by the fan 68 through this exhaust or exhaling compartment to create a suction therethrough for facilitating the scavenging of the armor, and removing the foul air therefrom.

The casing 69 also has an electric motor or prime mover 73 positioned therein and connected to the main operating shaft 74 to which a propeller 75 is connected. The propeller 75 is positioned exteriorly of the casing 69 and in such position that upon operation of the motor, the propeller will be rotated for driving the diver upwardly through the water, thus in case one of the hoses 62 or 63 becomes broken, and the diver 80 closes the valve 64, he can by starting the motor or prime mover 73 force himself to rise upwardly through the water, or he can, at any desired time, cause himself to rise independently of the usual mechanism for hoisting or drawing him upwardly 85 through the water.

The torso inclosing body 1 has suitable anchoring members 76 connected thereto to which the ordinary hoisting cables 77 are 90 attached.

The switch 80 is carried by the section 2 of the body 1 at the forward end of the same, and it has an operating lever 81 connected thereto and positioned exteriorly of the body 1 so that it may be operated by the diver at will to swing the movable contact 80 into engagement in either one or both of the stationary contacts 82 and 83. These stationary contacts 82 and 83 are insulated 100 from each other by a slot of insulation 84. The stationary contact 82 is connected to the motor 70 for operating the fan 68, while the stationary contact 83 is connected to the motor 73 for operating the propeller 75. 105 The feed wires which supply the current for the operation of the motors 70 and 73 extend downwardly from the ship or place from which the diver descends, being coiled about one of the hoisting cables 77 and indicated at 110, passing through a suitable opening 86 in the helmet, from whence they are connected to the stationary and movable contacts 82 and 83.

A suitable buoyant tank or float 88 is pivotally connected to the body 1 and assists the diver in raising himself with the assistance of the propeller 85.

From the foregoing description taken in connection with the accompanying drawings, it will be apparent that a metal diving suit, particularly adapted for deep sea diving has been provided which suit embodies flexibility to such an extent as to permit the diver to have use of practically all of the 115 120 125 130

joints of his body when under water; a suit which will prevent collapsing thereof against the body of the diver when he first enters the water, or when he engages an 5 undertow or undercurrent in the sea, eliminating the contingent inconvenience to the breathing and movement of the diver; a diving suit wherein a circulation of fresh 10 air will be maintained at all times, and also whereby the diver may, at his will, force 15 himself upwardly to the surface of the water without the assistance of the usual type of hoist; and it is to be understood that changes in details may be made without 20 parting from the spirit of the invention, but:

What is claimed is:

1. A submarine armor comprising a body portion provided with a helmet, a valve casing 20 providing a plurality of compartments communicating individually with the space within the helmet, oppositely opening valves controlling entrance and exit to the compartments, a valve common to said compartments and having operating means extending 25 on the outside of the casing.

2. A metal submarine armor comprising a body portion provided with a helmet, a

valve casing having a partition dividing the same into a pair of separate compartments, 30 said compartments communicating individually with the space within said helmet, oppositely opening flap valves controlling inlet and outlet of air between the helmet and said compartments, a single valve plug having ports within said compartments and arranged to control the passage of air there-through, an operating means for said plug extending exteriorly of the casing, a second casing carried by the body portion, a fan in 35 the second casing, and a pipe leading from the fan to a point in proximity to one of the compartments.

3. In a metal submarine armor, a body portion provided with a helmet, a valve casing 40 secured against one side of the helmet and having a partition therein forming separate chambers communicating with the helmet, flap valves carried by the valve casing controlling the inlet and outlet of air 45 with respect to the helmet, and a single valve element in the casing having ports arranged to control the passage of air through said chambers and provided with a handle exteriorly of the casing.

JOSEF KAMIENIECKI.
